DUST COLLECTOR FOR VACUUM
CLEANERS

Taylor P. Calhoun, Worcester, Mass.

Application May 9, 1933, Serial No. 670,112

12 Claims. (Cl. 183—52)

This invention relates to dust collectors for vacuum cleaners, and more particularly to a construction which may be connected to the discharge nozzle of an ordinary household vacuum cleaner and which will serve to collect the dust delivered from the nozzle in an air blast.

It has heretofore been customary to utilize for this purpose a filter bag formed of porous cloth which can be opened at its upper end to permit the removal of the accumulated dust from the bag. The removal of this dust is a dirty and disagreeable task, and in order to avoid the necessity therefor it has been proposed to construct the filter bag of a cheap material such as paper, so that the entire bag and its contents can be burned or otherwise disposed of. Such a large paper bag is necessarily somewhat expensive. Furthermore various difficulties have been encountered with constructions of this type. No paper has yet been discovered which is sufficiently porous to avoid excessive back pressure on the vacuum cleaner fan and which at the same time has adequate mechanical strength. The bags are frequently punctured by sharp corners on furniture. Moreover, they become worn through by the abrasive action of the accumulated mass of dirt, and they often crack as a result of the constant flexing as the cleaner handle is moved up and down.

In an attempt to provide a practical construction it has been proposed to utilize a long tube which slopes upwardly from the vacuum cleaner nozzle to the top of a small paper bag, it being the intention to deposit the dust in the bag through the action of the air blast. The tube in this prior construction is non-porous for most of its length. With such an arrangement there is not sufficient porous area available to relieve the air pressure. Furthermore only the finer dust particles reach the bag, and the larger particles drop back and clog the tube and the fan casing.

It is accordingly one object of the invention to overcome these difficulties and to provide a simple and inexpensive dust collector for vacuum cleaners which is so arranged that the accumulated dust may be readily removed without in any way exposing the operator to the dust.

It is a further object of the invention to provide a dust collector of ample mechanical strength which will provide a large porous area for the discharge of air and which will include a comparatively small cheap bag for the removal and disposal of the accumulated dust.

It is a further object of the invention to pro-

vide a dust collector including a permanent filter bag in which the dust accumulates in normal operation and a bag of paper or other cheap material releasably attached thereto, the parts being so arranged that by inverting the entire construction the dust will be deposited in the paper bag, whereupon the latter can be removed and burned.

It is a further object of the invention to provide a dust collector which will be simple and compact, and which will present an attractive appearance when mounted on a vacuum cleaner.

With these and other objects in view, the invention resides in the combination of parts set forth in the specification and covered by the claims appended hereto.

In accordance with my invention I provide a filter bag of a porous material, such as cloth, which may be attached to the discharge nozzle of a vacuum cleaner in the usual manner. This bag is shaped to retain an accumulated mass of dust and prevent it from dropping back into the fan casing. The filter bag is provided with a discharge opening, preferably at its upper end, and a receptacle or bag of paper or other cheap material is releasably attached to the filter bag in a position to close this opening. The paper bag may be clamped to a rigid ring, preferably circular in shape, which is secured to the filter bag. Inverting and shaking the filter bag will cause the dust to fall into the paper bag, which can then be removed and burned with the dust therein. The paper bag is preferably normally concealed and protected by a cover of cloth or other suitable material forming an upward extension of the filter bag, and this extension may have a long slit normally closed by a slideable fastener or other means.

Referring to the drawings illustrating one embodiment of the invention and in which like reference numerals indicate like parts,

Fig. 1 is a side elevation of a vacuum cleaner with my improved dust collector mounted thereon, certain parts being shown in section for clearness of illustration;

Fig. 2 is a view of the dust collector removed from the vacuum cleaner, showing the method of transferring the collected dust into the disposable receptacle;

Fig. 3 is an end view of the dust collector;

Fig. 4 is a view showing the dust collector opened to allow access to the disposable receptacle, the latter being shown in partial section for clearness of illustration;

Fig. 5 is an enlarged section through a portion

of the dust collector, the section being taken on the line 5—5 of Fig. 4;

Fig. 6 is a detail of the clamping ring, shown in open position;

5 Fig. 7 is a detail of the toggle clamp used with the clamping ring;

Fig. 8 is a detail of the hinged joint in the clamping ring;

10 Fig. 9 is a detail of the clamping ring, shown in closed position; and

15 Fig. 10 is a detail of the supporting ring, shown in section.

In the drawings I have illustrated a vacuum cleaner of the ordinary household type comprising a fan casing 20 provided with a forwardly and downwardly extending suction nozzle 21 and a rearwardly directed discharge nozzle 22. An electric motor 24 is mounted in the rear of the fan casing and serves to operate a fan (not shown) of the usual construction. Wheels 25 are shown beneath the motor to support a portion of the weight thereof. An operating handle 26 is hinged to the motor and fan casing assembly and extends rearwardly therefrom, being free to swing up and down in a vertical plane as is customary in machines of this type. These various parts are all well known in the art, and hence do not require detailed description or illustration.

20 In order to collect the dust discharged from the nozzle 22 and at the same time allow the air to escape, I provide a filter bag 28 of a suitable porous material such as cloth, which is normally supported in an inclined position on the vacuum cleaner. The lower or inlet end of the bag is 25 provided with a restricted inlet neck 23 to which a collar 30 is secured. This collar is provided with opposed hooks 39 or other suitable means whereby it may be releasably attached to the nozzle 22. As shown in Fig. 1, the bag 28 is so shaped that in normal operation, it will retain an accumulated mass of dust 27 which is delivered to the bag in an air blast from the nozzle 22. This dust collects at the bottom of the bag and slightly in the rear of the inlet neck 23.

30 After a considerable quantity of dust has been collected, it is necessary to empty the bag. In order that this may be done without the necessity for exposing the dust to the atmosphere, I form the bag with a discharge opening which is preferably located at the upper end of the bag opposite to the inlet neck 23, and I provide a receptacle 29 which may be releasably attached to the bag in a position to close the discharge opening. This receptacle is shown as a comparatively small bag, and it may be formed of paper or other inexpensive material. The paper is preferably somewhat porous, as this will reduce the back pressure on the vacuum cleaner, but a non-porous paper may be used if desired.

35 In order to facilitate the attaching of the receptacle 29 to the filter bag 28, I preferably provide a rigid circular ring 31 (Figs. 5 and 10) which surrounds the discharge opening in the filter bag. This ring is considerably larger than the inlet collar 30 and it is permanently secured to the filter bag by sewing or otherwise. In the preferred construction illustrated the ring 31 is secured to an annular member 32 of cloth or other flexible material which is fastened to the interior 40 of the main body portion of the filter bag. The receptacle 29 is shaped to fit over the outside of the ring 31, and these parts are firmly but releasably held together by means of a clamping ring 33. The ring 31 is formed with a circumferential groove 35 which cooperates with the clamping

ring in ensuring a tight joint. The clamping ring 33 may be formed in two parts which are hinged or jointed at 36, and one part may be provided with a toggle clamp 37 which engages with a hook 38 on the other part and thus serves to draw the parts together.

45 For the purpose of concealing and protecting the paper bag 29, I preferably provide a cover 40 of cloth or other suitable material forming an upward extension of the filter bag 28. This cover 40 is formed with a long slit or opening 41 therein through which access may be had to the paper bag. A slideable fastener 42 of the well-known "Zipper" type provides a convenient means for closing the slit. It will be noted that structurally 15 the filter bag 28 and cover 40 form an inclined tubular member having an opening at its upper end, and the flexible annular member 32 extends around and is secured to the interior of the tubular member intermediate the height thereof. 20

25 In order to support my improved dust collector on the vacuum cleaner, I preferably provide means whereby the upper end of the cover 40 may be releasably attached to the vacuum cleaner handle 26. For this purpose I have shown a small spring 45 attached to the cover 40 and adapted to engage a hook 46 on the handle 28.

30 The operation of the invention will now be apparent from the above disclosure. The dust collector is mounted on the vacuum cleaner as shown 35 in Fig. 1. Dust is drawn in through the nozzle 21 by the fan and discharged in an air blast into the filter bag 28. The air escapes through the porous wall of the bag, and the dust accumulates in a heap 27 at the bottom of the bag. When it is desired to empty the bag, the motor will be stopped, the spring 45 removed from the hook 46, and the collar 30 disconnected from the nozzle 22. The operator will then invert the filter bag, preferably grasping the collar 30 as indicated in Fig. 2 40 and shaking the bag up and down. This will cause the accumulated dust to drop through the ring 31 and into the receptacle 29. The slideable fastener 42 will then be pulled around to unfasten the slit 41, so that the cover 40 may be turned 45 back as shown in Fig. 4 to expose the receptacle 29. The clamping ring 33 can then be released, allowing the receptacle 29 to be removed and destroyed with the dust contained therein. A new receptacle can then be attached to the filter bag. 50

55 It will be noted from an inspection of Fig. 4, that the relative sizes of the receptacle 29 and cover 40 are such that when the filter bag is inverted and shaken the cover will form a support for the receptacle and prevent any undue strain 55 thereon.

60 From the above description it will be apparent that I have provided a dust collector which can be conveniently emptied without touching the dust or exposing it to the atmosphere. The paper bag 60 is fully protected and concealed by the cover, and since no dirt accumulates in this bag in normal operation, it is not subjected to the abrasive action of accumulated dirt. The filter bag is fully capable of withstanding constant flexing as the cleaner 65 handle is moved, and provides a large porous area for the discharge of the air. Furthermore, the filter bag serves to retain the accumulated dust and prevents it from dropping back into the fan casing. The entire dust collector is simple and 70 inexpensive to manufacture, and attractive in external appearance.

75 Having thus described my invention what I claim as new and desire to secure by Letters Patent is:

1. A dust collector comprising a porous filter bag provided with an inlet opening and a discharge opening and shaped to retain an accumulated mass of dust, and a receptacle releasably attached to the bag and closing the discharge opening, the receptacle being normally free from contact with accumulated dust, and the parts being so constructed and arranged that changing the position of the filter bag will cause the dust to drop into the receptacle, which can then be removed and destroyed. 5
2. A dust collector comprising a filter bag formed of porous cloth and provided with an inlet and a discharge opening, the bag being shaped to retain an accumulated mass of dust, and a paper bag releasably attached to the filter bag and closing the discharge opening, the paper bag being normally free from contact with accumulated dust, and the parts being so constructed and arranged that changing the position of the filter bag will cause the dust to drop into the paper bag, which can then be removed and destroyed. 10
3. A dust collector comprising an inclined porous filter bag having an inlet opening at its lower end and a discharge opening at its upper end, the bag being shaped to retain an accumulated mass of dust, and a receptacle releasably attached to the bag and closing the discharge opening, the receptacle being normally free from contact with accumulated dust, and the parts being so constructed and arranged that inverting the filter bag will cause the dust to drop into the receptacle, which can then be removed and destroyed. 15
4. A dust collector comprising an inclined porous filter bag having a discharge opening at its upper end and an inlet neck at its lower end provided with a collar which is adapted to be connected to the discharge nozzle of a vacuum cleaner, the bag being shaped to retain an accumulated mass of dust below and adjacent to the inlet neck, and a receptacle releasably attached to the bag and closing the discharge opening, the receptacle being normally free from contact with accumulated dust, and the parts being so constructed and arranged that suspending the bag by the collar will cause the dust to drop into the receptacle, which can be removed and destroyed. 20
5. A dust collector comprising an inclined porous filter bag having an inlet neck at its lower end and a discharge opening at its upper end, the bag being shaped to retain an accumulated mass of dust below and adjacent to the inlet neck, a collar secured to the inlet neck and adapted to be connected to the discharge nozzle of a vacuum cleaner, a rigid annular member secured to the bag and surrounding the discharge opening, and a receptacle releasably attached to the annular member and closing the discharge opening, the receptacle being normally free from contact with accumulated dust, and the parts being so constructed and arranged that suspending the bag by the collar will cause the dust to drop through the annular member and into the receptacle, which can then be removed and destroyed. 25
6. A dust collector comprising an inclined porous filter bag having an inlet neck at its lower end and a discharge opening at its upper end, the bag being shaped to retain an accumulated mass of dust below and adjacent to the inlet neck, a circular collar secured to the inlet neck and adapted to be connected to the discharge nozzle of a vacuum cleaner, a circular ring secured to the bag and surrounding the discharge opening, and a receptacle releasably attached to the ring and closing the discharge opening, the receptacle being normally free from contact with accumulated dust, and the parts being so constructed and arranged that suspending the bag by the collar will cause the dust to drop through the ring and into the receptacle, which can then be removed and destroyed. 30
7. A dust collector comprising an inclined porous filter bag having an inlet opening at its lower end and a discharge opening at its upper end, the bag being shaped to retain an accumulated mass of dust, a receptacle releasably attached to the bag and closing the discharge opening, and a cover forming an upward extension of the filter bag and normally serving to conceal and protect the receptacle, the cover having an opening therein through which access may be had to the receptacle, the parts being so constructed and arranged that inverting the filter bag will cause the dust to drop into the receptacle, which can then be removed and destroyed. 35
8. A dust collector comprising an inclined filter bag of porous cloth having an inlet opening at its lower end and a discharge opening at its upper end, the bag being shaped to retain an accumulated mass of dust, a paper bag releasably attached to the filter bag and closing the discharge opening, and a cover forming an upward extension of the filter bag and normally serving to conceal and protect the paper bag, the cover having an opening therein through which access may be had to the paper bag, the parts being so constructed and arranged that inverting the filter bag will cause the dust to drop into the paper bag, which can then be removed and destroyed. 40
9. A dust collector comprising an inclined porous filter bag having an inlet opening at its lower end and a discharge opening at its upper end, the bag being shaped to retain an accumulated mass of dust, a receptacle releasably attached to the bag and closing the discharge opening, a cover forming an upward extension of the filter bag and normally serving to conceal and protect the receptacle, the cover having a long slit therein through which access may be had to the receptacle, and means including a slidably fastener for closing the slit, the parts being so constructed and arranged that inverting the filter bag will cause the dust to drop into the receptacle, which can then be removed and destroyed. 45
10. A dust collector comprising an inclined porous filter bag having an inlet opening at its lower end and a discharge opening at its upper end, the bag being shaped to retain an accumulated mass of dust, a receptacle releasably attached to the bag and closing the discharge opening, a cover forming an upward extension of the filter bag and normally serving to conceal and protect the receptacle, the cover having an opening therein through which access may be had to the receptacle, and means to maintain the opening in the cover normally closed, the parts being so constructed and arranged that inverting the filter bag will cause the dust to drop into the receptacle, which can then be removed and destroyed, the relative sizes of the receptacle and cover being such that when the filter bag is thus inverted the cover will form a support for the receptacle. 50
11. A dust collector comprising an inclined tubular member of flexible material having a restricted inlet neck at its lower end, a collar secured to the inlet neck and adapted to be connected to the discharge nozzle of a vacuum cleaner, a circular ring secured to the tubular member and surrounding the inlet neck, and a receptacle releasably attached to the ring and closing the discharge opening, the receptacle being normally free from contact with accumulated dust, and the parts being so constructed and arranged that suspending the tubular member by the collar will cause the dust to drop through the ring and into the receptacle, which can then be removed and destroyed. 55

nected to the discharge nozzle of a vacuum cleaner, the tubular member having an opening at its upper end, means for maintaining the opening normally closed, a flexible annular member extending around and secured to the interior of the tubular member intermediate the height thereof, a rigid ring secured to the annular member, and a bag located within the upper portion of the tubular member and releasably attached to the ring,

10 the lower portion of the tubular member being shaped to retain an accumulated mass of dust, and the parts being so constructed and arranged that inverting the tubular member will cause the dust to drop into the bag, which can then be removed and destroyed.

12. A dust collector comprising an inclined tubular member formed of porous cloth and having a restricted inlet neck at its lower end, a collar secured to the inlet neck and adapted to be con-

nected to the discharge nozzle of a vacuum cleaner, the tubular member having an opening at its upper end, means for maintaining the opening normally closed, a flexible annular member extending around and secured to the interior of the tubular member intermediate the height thereof, a rigid ring secured to the annular member and having an opening therethrough considerably larger than the opening through the collar, and a paper bag located within the upper portion of the tubular member and releasably attached to the ring, the lower portion of the tubular member being shaped to retain an accumulated mass of dust, and the parts being so constructed and arranged that inverting the tubular member will cause the dust to drop into the bag, which can then be removed and destroyed.

TAYLOR P. CALHOUN.
